tion of Massachusetts

Filed Oct. 17, 1968, Ser. No. 14,042

Term of patent 14 years

Int. Cl. D10—04

U.S. Cl. D42—7

FIG. 1

FIG. 2

FIG. 3FIG. 4FIG. 1 is a perspective view of a watchman's clock, showing my new design,

FIG. 2 is a front elevational view of the clock,

FIG. 3 is a rear elevational view of the clock, and

FIG. 4 is a side elevational view of the clock.

In all figures, a conventional carrying strap is shown fragmentarily for convenience of illustration. It is to be understood that the strap continues about the bottom of the casing within the recess indicated in FIG. 4.

I claim:

The ornamental design for a watchman's clock, as shown and described.
